UNITED STATES PATENT OFFICE.

GEORGE J. ENGERT, OF SPOKANE, WASHINGTON.

HOLLOW CONCRETE WALL.

Original application filed February 6, 1922, Serial No. 534,605. Divided and this application filed September 27, 1922. Serial No. 590,872.

To all whom it may concern:

Be it known that I, GEORGE J. ENGERT, a citizen of the United States, residing at Spokane, in the county of Spokane and 5 State of Washington, have invented certain new and useful Improvements in Hollow Concrete Walls, of which the following is a specification.

This application is a division of an application filed by me February 6, 1922, Serial No. 534,605.

The present invention has for its object the provision of a wall which will possess the strength of a solid wall and will contain 15 an air chamber which may be a dead-air chamber to avoid the presence of moisture and transmission of sound or may provide circulation through the entire height of the wall to permit foul air to escape through it 20 beneath the roof of the building. The invention is illustrated in the accompanying drawing and resides in certain novel features which will be hereinafter first fully described and then more particularly pointed 25 out in the appended claims.

The drawing is a perspective view of a portion of a wall embodying my invention.

In constructing a wall according to my invention, I employ inner and outer false work or forms, the height of which is increased as the work progresses. At intervals corresponding to the courses of the wall, tension wires 3 are secured in and extend through the falsework to prevent outward 35 collapse or spreading of the falsework. The foundation of the building may be a solid structure or may be hollow, as preferred, and the falsework will, of course, rise from the foundation at the opposite sides of the same. 40 Vertical reinforcing rods 5 are embedded in the foundation and rise therefrom at suitable intervals to extend to the height to which it is desired to carry the wall. Upon the upper surface of the foundation and 45 upon each course of the wall as it is formed, I place a base plate 6 with its side edges at opposite sides of the longitudinal center of the wall and between the reinforcing rods 5. Along the side edges of this base plate 6, 50 I provide openings in which are secured tie wires 8 which are wrapped about and secured to the vertical reinforcing rods so as to hold the base plate firmly in position. Substantially U-shaped slits are formed in 55 the base plate, thereby producing tongues 9

which may be struck up from the slits, the spaces originally occupied by the several tongues producing openings 10 through which air may circulate in the completed wall. The base plate having been secured in 60 position, a form or core is placed upon the base plate so as to rest thereon between the upstanding tongues and be held in position upon the plate by said tongues, the core or form preferably flaring upwardly. 65

To form the wall, green concrete is poured into the space between the opposed sides of the falsework and directed into the spaces between said falsework and the respective sides of the form, the pouring being continued until the level of the poured concrete reaches the top of the form. The concrete is then permitted to partly set and when it has set sufficiently to permit movement of the form, the form is lifted to a point above the 70 partly finished wall. A second base plate 6 is then placed in position over the partly finished wall and the described operation is repeated until the wall has reached the desired height, each successive base plate 6 75 being left embedded in the wall and constituting a reinforcement therefor. After the wall is finished, the falsework is, of course, removed and the projecting ends of the tension wires 3 are cut off flush with the 80 surfaces of the wall. At proper intervals, removable cores may be placed in position in openings provided therefor in the falsework so that sockets or openings, indicated at 22, will be produced. 85 90

It will be readily understood from the foregoing description, taken in connection with the accompanying drawing, that I have devised a hollow concrete wall which may be rapidly produced and a strong structure 95 obtained at a low cost.

Having thus described the invention, what is claimed as new is:

1. A hollow concrete wall having vertical reinforcing rods embedded therein between the sides of the wall and the hollow central portion thereof, and horizontally disposed plates embedded in the wall at intervals and bridging the central hollow space, said plates having openings therethrough 100 and being connected with the vertical reinforcing rods. 105

2. A hollow concrete wall having vertical reinforcing rods embedded therein between the sides of the wall and the central hollow 110

space thereof, horizontally disposed plates having their edges embedded in the members of the wall, and tie wires connecting the edges of said plates with the vertical reinforcing rods, said plates having openings therethrough in the portions thereof which bridge the hollow of the wall.

3. A hollow concrete wall having a central

longitudinal chamber, vertical reinforcing rods embedded in the wall at opposite sides of said chamber, and vertically spaced plates embedded in the wall and connected with the vertical reinforcing rods, said plates bridging the chamber in the wall. ¹⁰

In testimony whereof I affix my signature.

GEORGE J. ENGERT.
